Regd. Apr. 28/69

United States Patent Office.

D. FRANK DUNHAM, OF AUBURN, NEW YORK.

Design No 3,501, dated May 18, 1869.

DESIGN FOR A CLOTHES-LINE HOLDER.

The Schedule referred to in these Letters Patent and making part of the same.

To all whom it may concern:

Be it known that I, D. FRANK DUNHAM, of Auburn, in the county of Cayuga, and State of New York, have invented certain new and useful Improvements in Clothes-Line Holders; and I do hereby declare the following is a full, clear, and exact description thereof, reference being had to the accompanying drawing, and to the letters of reference marked thereon, which form a part of this specification, and in which is represented a front view of my clothes-line fastener.

The nature of my invention consists in the novel manner of forming a clothes-line holder; and to enable others to make and use it, I will describe both its form and construction.

In the accompanying drawing—

A represents the holder, provided at one end with the projection B, curved at both ends, as seen at *b b*.

C is a pivoted clamp, formed at its lower end with a slotted projection, *a*, for clamping the line.

What I claim, and desire to secure by Letters Patent, is—

A clothes-line fastener, when formed or cast as described.

In testimony that I claim the foregoing as my own, I affix my signature, in presence of two witnesses.

Witnesses: D. FRANK DUNHAM.

PETER P. RYNDERS,
R. D. DOREMUS.
